UNITED STATES PATENT OFFICE.

MAXIMILIAN ALMA AND CARL EGON ALMA, OF VIENNA, AUSTRIA.

DRAW AND BUFFER GEAR FOR RAILWAY VEHICLES.

Application filed September 15, 1924, Serial No. 737,815, and in Austria September 21, 1923.

This invention relates to a draft mechanism for railway cars of the type extending from end sill to end sill, and has for its object to provide a device more particularly 5 adapted for use with long and heavy cars; to automatically permit, when travelling coupled on the curves, an adjustment of the draw-head to suit the curve and to avoid unfavorable strains on the coupling or draw-heads; to permit vertical movement of the draw-head; to permit the use of a readily renewable or exchangeable draw-head and its shank, the latter being short; to distribute both the pull and thrust to different points 10 along the axis of the car with the maximum pull and thrust transmitted to the centre of the floor frame.

The structure is such that the draft gear and the draw-bar mechanism connected to its 20 two ends are only movable longitudinally under the action of the compression and pulling forces, while the end parts comprising the coupler heads and their shanks, are not only movable longitudinally of the axis of the vehicle, but can also turn or swing in the horizontal plane, and in other planes if so desired.

Referring to the drawings, in which like parts are similarly designated—
30 Figure 1 is a plan view of a draw-bar mechanism.

Figs. 2-5 are details thereof.

Fig. 6 is a modified form of such mechanism.

Fig. 7 is a detail view thereof.

Figs. 8-10 show different forms of draw-bar mechanism operating on the same principle.

Figs. 11-17 are views partly in section 40 of one end section of the draft gear rod showing different arrangements.

Fig. 18 is a longitudinal section, and

Fig. 19 is a plan view of the central member connecting the two sections of the draw-bar.

The main rod 32 of the draft gear, only a portion of which is shown, is only movable in the direction of the longitudinal axis of the car, and is movably connected in the 50 centre of the car to the rod 32 of the second

half of the car by means of a suitable connection and carries the shock absorbing springs.

The method of guiding, and details of construction of the turning parts (draw-head and shank) depend in the case of centrally arranged couplings, on the nature of the draw-head and its shank.

1. If the draw-head is such that it yields to forces which do not act centrally of the car and swings horizontally, as well as otherwise, the draw-head and shank must be properly guided from the truck (Figs. 1 to 6) by a guide such as a Figs. 1, 4 and 6.

2. If, however, the draw-head is such that it connects stiffly with the head of the adjoining car, the drawhead and its shank must be mounted so far as to swing freely in the main frame of the car (independently of any bogie) (Figs. 8 to 10).

The limitation of the direction of swing and its extent is dependent only upon a suitable shaping of the opening in the end sill of the car.

According to this invention the turning 75 parts (draw-head and shank) in each half of the car are jointed to the non-turning parts (draw-bar mechanism) in such a manner that, at least in the case of compression forces, any rings are prevented from striking bolts or the like, and the shank, in case of shocks, must strike a strong transverse member.

In Figure 1, the shank 2, carrying the 85 diagrammatically indicated draw-head 1, is guided and swung in a bearing *a* secured to the bogie or truck of the car, and has the required freedom of movement to the right and to the left in the opening through the end sill *b*, which opening is guarded by a plate *n*.

The rails *d* secured to the floor frame of the car (to the centre sills *c*) guide the draw-bar mechanism comprising a frame constituted by cross members 4 and 6 and longitudinal members 5. This frame is movable in the direction of the longitudinal axis of the car.

The shank 2 passes through the cross member 4 and can swing laterally in the 100

same; it carries a sleeve 7 which at the top and bottom has an integral pin of square cross-section and terminates in a cylindrically rounded off rear projection 3 (with vertical axis) to which corresponds a hollow cylindrical recess in the cross member 6.

The cross-section of the shank 2 is preferably square from the draw-head to a point within the sleeve 7, and the sleeve 7 is locked on the shank 2 by means of a nut 9, or clips 61, (Figs. 2 and 3). Square pins 8 projecting from sleeve 7 pass through square holes in two parts 10, one of which is arranged above and the other below the sleeve 7 and the nut 9 and the shank 2, so that both parts 10 participate in the movements of the shank 2 relatively to the draw-gear, which is movable only in the longitudinal direction.

The parts 10 are formed into loops or shackles at the back, and said shackles engage round pins 13 provided at the top and at the bottom of a sleeve 12, said shackles being capable of swinging about said pins as a centre. The sleeve 12 is mounted on a rod 32 movable only in the longitudinal direction and locked on the same, on the one hand, by the edges of the rod 32 which has a square cross-section from a point inside the sleeve 12, to a point behind the transverse sill e.

In the position of rest the shackles of the parts 10 are held in contact with the pins 13 by the action of springs 15, and the projection 3 has so much free play in the recess of the cross member 6 that during the pull on a curve the necessary turning of the parts 10 about the pins 13 is not interfered with. In the case of a shock on a curve, the round projection 3 is forced into and turns in the recess in the cross member 6. In case of a shock, a clearance is produced between the loops 10 and the pins 13 which is sufficient to avoid interference by the pins 13 with the turning of the shank and its projection 3 in the recess in the cross member 6.

Any pull is transmitted to the draw-rod 32 by the parts 10, while thrust is transmitted to the rod 32 by means of the cross member 6 against which the rod 32 is pressed by springs of the draft gear, (the real draw and buffer springs) arranged between it and the car frame. The shank 2 is swung on curves by the guide a on the truck to and from its central position.

To render the draw-heads more easily interchangeable the shank 2 may be made in two parts held together by an easily detachable connection that will insure their invariable relative position. Such a connection is shown in Figure 4. The bolts 18 are merely intended to hold fast the two parts 17. The flange 19 forms a gripping member.

Figure 5 shows in a longitudinal section

through the frame 4, 5, 6, Fig. 1, the manner of connecting the longitudinal member 5 to the cross members 4 and 6.

When the pivot pin f (Fig. 6) of the truck projects within reach of the draw mechanism it can be avoided by lengthening the guide frame as indicated. The sleeve 12 with the pins 13 (Fig. 1) is replaced in Figure 6 by a plate 60 provided with the pins 13 and secured to the cross member 6.

Figure 7 is a longitudinal section showing the parts 20 of Figure 6. The bolts 23 are merely used for securing the part 20 to the cross members 63, 21 and 22.

In the constructions shown in Figs. 8 and 9, no guide for the draw-head shank 2 is provided on the truck of the car. In these figures the shank 2 is shown as passing through the end sill b provided with an opening allowing the swing, and loosely through the cross member 28 of the sliding frame or its equivalent in which it can also swing to a corresponding extent. The shank 2 has preferably a rectangular cross-section for limitation of the rotation of said shank on its axis by the guard plate n. In the position of rest, when turning should not only be possible in a horizontal plane but also in the vertical plane, the shank 2 is inclined downward very slightly, and rests on the (rounded-off) bottom edge of the opening in the end sill b and guard plate n. During the coupling the shank 2 is automatically raised.

A cross head 24 is mounted on the shank 2 and is prevented from moving toward the draw-head by a thickened portion or shoulder of said shank 2. This cross head engages the heads of rods 25 that are movable through the cross members 28 and 67 (Fig. 8) or 28 and 69, (Fig. 9) of the sliding frame. On these rods are mounted the centering springs 26 which are slightly compressed by means of nuts 27. Instead of said springs and rods 25, a centering spring may be mounted on the shank 2 itself, as shown in Fig. 10. If the shank 2 is constructed as shown in Fig. 4, the recesses in the two parts 17, required for their assembly, are preferably to be provided only in their two lateral walls.

The cross members 28 and 67, (Fig. 8) or 28, 69 and 21 (Fig. 9) of the sliding frame of the draw-bar mechanism are guided in rails d and are secured together by means of the longitudinal members 5 (Fig. 8) or 31 (Fig. 9) in the manner shown in Figure 5.

On the shank 2 behind the cross member 28 is mounted a thick sleeve 29 secured to the shank 2 in the same way as the sleeve 7 (Figs. 1 and 2). The sleeve 29 is provided at its top and bottom with a projection 30, the round end of which is preferably given a spherical shape, the round portions of the two projections 30 having the same centre.

Corresponding to these rounded off portions are hollow spherical recesses in the cross member 28, a kind of ball-and-socket joint thus being formed, which enables the shank 2 to turn when subjected to pull or tension. The shank 2 terminates, as before, in a projection 3, which is also preferably given spherical shape that corresponds to a spherical recess in the cross member 65.

10 In the position of rest, the projections 30 engage with the recesses in the cross member 28, and the projection 3 has a certain amount of play in the recess of the member 65, so that the parts can turn freely under tension.

15 Under impact or compression the pivot for the shank is shifted from 30 to 3, the projection 3 engaging (the centering springs being at the same time compressed) in the recess in the cross member 65, thus produc-

20 ing the clearance required for the swing of the projections 30 in the recesses of the cross member 28, whilst the projections 3 and the recess in the cross member 65 form a pivot joint for the swinging of the shank 2. If

25 the two projections 3 and 30 are described from the same centre, the clearances in question can be reduced to a minimum. The cross member 65 engages (by means of the walls of a recess provided in it) with the

30 draw rod 32 movable longitudinally of the car, and compression is transmitted to the said rod directly by the cross member 65 (Fig. 8) or 21 (Fig. 9), while any tension is transmitted by the pull of the cross mem-

35 ber 21 (Fig. 8) or 22 (Fig. 9) on the thickened portion or head 11 of the rod 22, (or eventually to a nut provided in place of the said head).

40 In the construction shown in Figure 10 the draw-head shank 2 is reduced at the portion passing through the cross member 74 of the frame 76, longitudinally slidable on the rails *d*, and is carried through the said cross member as well as through the centre of a spring seat 57 with sufficient clearance for swinging. In the case of a shock, or compression, the shank end 73 seats in the recess in the front wall of the cross member 74, but when the draw-head is pulled the rounded front end of the nut 75 seats in its corresponding recess in the rear wall of the cross member 74, at the same time permitting the shank 2 to swing.

45 The draw-rod 32 is secured in the cross member 78 of the sliding frame 76 by means of the nut 77.

50 The spring 76, or two concentric springs if one is not sufficient, for returning the shank 2 back to the central position, is mounted between seats 71 and 57. The seat 71 is secured to the shank 2, and the seat 57 to the cross member 74. The shank 2 is preferably made of square cross-section down to the seat 71, or to a point within this seat.

55 The seat 57 is fixed to the cross member 74

either by means of pins 58 projecting into openings in the cross member 74, or by means of a horizontal rib of round cross-section with which it is provided on the left and right hand sides, engaging with corresponding horizontal notches in the cross member 74, so that the seat can turn about the axis of the said ribs, while shank 2 swings, the seat 57 does not yield, thus bending the spring 72, which tends to return the shank to central position. (Lateral movement of the seat 57 is rendered impossible by the dimensions of said notches).

60 The expanding and contracting draft gear to which the draw-bar mechanisms are connected, has two draw-bar sections 32 movable in a central, adjustable part, that makes it possible to arrange several impact or tension springs in each half of the car for the purpose of ensuring the powerful spring action required for heavy cars subjected to large impact forces, and at the same time gives the required degree of elasticity upon initiation of the impact.

65 When using several springs, it is advisable, in order to avoid particularly hard initial action of the springs, to construct the draft gear so that its parts shall in the case of a pull or of an impact be opposed by the springs that come successively into action.

70 It may be further advisable to provide, in addition to the springs acting on the floor frame, auxiliary springs, which in case of shocks at both ends, act only or chiefly without causing a contraction of the draft gear, and the arrangement may be such that, owing to the rapidity of action of the impact on the draft rod of the second car half and to the movement of the said rod in the direction of the shock, the impact is at once transmitted to the draft gear of the next car.

75 A few examples of the many possible variations of this spring arrangement will be now described.

80 In Figs. 11 to 19, *g*, *h*, *i*, *j*, *l* and *m* are bearings, abutments or sills secured to the floor frame, and 33, 35, 38, 40, 47 and 49 plates forming spring seats; 87, 91 and 92 are flanged pipes slidable on the draw rods, flanges of which form spring seats between which are arranged the main springs 34, 39, and the auxiliary springs 48. *K* is an intermediate floor frame sill. The devices are symmetrically arranged in both halves of the car. *M* is the centre of the car. Only half of the central connection element 43 for the two halves of the draft gear is shown in Figs. 11 to 18.

85 In Fig. 11 upon impact, first the spring 39 is compressed against the fixed abutment *j* by means of the sleeve 36 secured to the draft rod 32 by a cotter 37; as soon as the shoulder 46 has reached the washer 33 the spring 34 will be compressed against the fixed

130

abutment *h*. In case of a violent impact on both ends, all the springs on both ends of the car will be affected, and the draft rods 32 will meet inside the central sleeve 43. Upon impact at one end, the cotter 37 is limited by stationary stop *i*. It will be noted that in the neutral position of rod 32 the distance of the cotter 37 from its abutment *i* is greater than half the distance between the ends of the two rods 32 in sleeve 98.

The cotter 45 moves in slots 44 of the central connecting sleeve 43, and the slots are so made that upon shock the ends of the draft rods 32 abut, or that the cotters 45 strike the ends 98 of their slots. The former arrangement is preferable. Upon shocks applied at both ends all springs on both halves 32 of the draft rod come into action and the residual shock is transmitted by abutment from one half to the other.

In case of a pull the spring 39 will be compressed against the fixed abutment *i* by the movement of the sleeve 41 secured to the draft rod 32, and as soon as the sleeve 36 has reached the seat 35, the spring 34 will also be compressed against the fixed abutment *g*. In case of traction on both ends the two cotters 45 will strike the ends 99 of the slots 44 of the connection part 43.

Shocks are taken up through spring 39 acting against abutment *j* near the centre of the floor frame, and through the spring 34 against the abutment *h*; and in case the shock is at one end, or the shock at one end is greater than that on the other end, then the shocks are taken up by the striking of one of the cotters 37 against the abutment *i*. The floor frame is thus engaged at a plurality of points.

Pull is exerted on abutment *i* by spring 39 near the middle of the car; stronger pull causing spring 34 to also act on abutment *g*. When the pull is at one end, or when the pull at one end is greater than that at the other end, the cotter 42 engages abutments *j* near the car centre, so that the pull will be distributed to several points along the axis of the car.

In Fig. 12, in case of an impact, first the spring 34 will be compressed by the cotter 79 against the fixed abutment *i*, and as soon as the shoulder 81 has reached the seat 87 the main spring 39 will also be compressed against the fixed abutment *j*. In case of tension, the main spring 39 will be compressed against the fixed abutment *i* by the sleeve 41 secured to the rod 32, but the spring 34 will not be affected.

The construction may also be such that the shoulder 81, Fig. 12, will engage the seat 87 directly, and a small clearance will be provided between the cotter 79 and the seat 83; in case of an impact, the main spring 39 will be affected first, and the auxiliary spring 34 only afterwards.

In Fig. 13, in case of a shock at one end, first the main spring 39 will be compressed against the fixed abutment *j*, the sleeve 41 secured to the rod 32 also moving the seat 47 and compressing the auxiliary spring 48. The central sleeve 43 will be moved in the direction of the thrust, and at the same time the auxiliary spring 48 in the second half of the car will be pressed against its fixed abutment *l*.

In the case of impact at both ends, first the two main springs 39, and then the two auxiliary springs 48 will be compressed.

In the case of pull or traction at one end, first the spring 39 will be pressed against the abutment *i*, and as soon as the cotter 45 has reached the end 99 of the slot 44 in the connection sleeve 43, the auxiliary spring 48 will also be pressed against the abutment *l*, by the sleeve 43 moving in the direction of the pull. In case of a pull on both ends, the main springs 39 will be compressed, and according as the pull is stronger at one end than at the other, the auxiliary spring 48 will also be affected.

The construction in Fig. 14 differs from that of Fig. 13 chiefly by the presence, between the fixed abutments *l* and the flanged pipe 21 that replaces the disc 47, (Fig. 13), of a clearance, so that impact at one end will be transmitted by the auxiliary springs 48 of the two car halves, upon movement of the sleeve 43, to the draft rod of the second car half, which will be accordingly pushed out of the car in the direction of the impact and will therefore act at once on the draw-bar mechanism of the adjoining car, while at the same time the main spring 39 of the second car half will also be pressed against its abutment *i*.

In Fig. 15, in the interior of the sleeve 43 is provided a second sleeve 50 secured to the draw rod 32 by the cotter 45, so that in case of a pull, the auxiliary spring 48 will also be compressed against the fixed abutment *l*, after the disc 47 has moved against the latter.

In the construction shown in Fig. 16 impact at both ends will be taken up by the central sleeve 93 with which the flanged pipes 47 engage at both ends when the auxiliary springs 48 are compressed. The sleeve 50 (in the outer sleeve part 93) acts in the same way as the sleeve 50 in the construction shown in Fig. 15. Moreover, all cotters are avoided in the construction illustrated in Fig. 16. The sleeves 84 and 88 are formed as nuts, and are intended both for compressing the main springs 39 and for connecting together the draw-rod sections meeting in them. The disc 59 transmits the pressure to the sleeve 51 and, through the latter, to the flanged pipe 47. The cotter 45 of Fig. 15 is replaced in Fig. 16 by the sleeve 94 held by the nut 53, which,

after a suitable movement in the direction of the pull, strikes the head connection sleeve 93. The connection sleeve 93 is made, for the purpose of facilitating the erection, in two semi-cylindrical parts held together by a pair of straps 52 at each end.

In Fig. 17, the cotters are replaced by socket couplings constituted by pairs of connected semi-cylindrical shells 80 and 90 fitting exactly into peripheral grooves of the rod sections to be connected together. The central sleeve is replaced by two thick plates 97. Movable in the slots 96 of the said plates are pins 54 provided on the sleeve 55. The two plates 97 are connected together by clips 95, and the sleeve 55 is held to the rod by the cups 56 connected together. The sleeve 50 acts in the same manner as in the construction of Figs. 15 and 16.

Fig. 18 shows the two plates 97 and the parts situated between in vertical, longitudinal section.

Fig. 19 shows the plate 97 in plan.

In case of impact at one end, the auxiliary spring 48 is compressed against the flange plates 92 by coupling 90 and sleeve 51, and owing to the movement of said flange plates and compression of the auxiliary spring 48 in the second half of the car, the main spring 39 is compressed against the fixed abutment *i* of the second half of the car by means of the sleeve 51, coupling 90 and sleeve 41. When the coupling 80 of the first half of the car strikes the disc 33, the springs 34 and 39 of the first half of the car are compressed against their abutments *i* and *j*. Impact at both ends causes the auxiliary springs 48 in both halves of the car to be compressed against the plates 97, and the main springs 34 and 39 against the abutments *i* and *j*. The impact will be taken up either, after the engagement of the two discs 47 with the flanges 92, by the plates 97, or according to the dimensions adopted, by the meeting of the inner end of the rods 32.

In case of a pull at one end, the main spring 39 will be compressed against the fixed abutment *i*, the auxiliary spring 48 together with the sleeve 50 moves in the direction of the pull, and as soon as the disc 47, has engaged with the abutment *l*, the auxiliary spring 48 will also be compressed. Pull on both ends will cause both main springs 39 to be compressed against the abutments *i*, and the pull will be taken up by the pins 54 and plates 97, eventually with compression of the auxiliary springs 48 (after movement of the discs 47 to the abutment *l*).

The plates 97 instead of being arranged above and below the rods 32, may be arranged at the side of the same, and the pins 54 would then be arranged horizontally.

Pipes are used for the springs, having

flanges at one end that act as spring seats, 65 while their opposite unflanged ends operate to limit the compression of the springs.

In all the constructions the movement of the draft rod of the draw-gear is limited in one half of the car by the striking of cotters 70 or of flamed pipes against abutments or discs provided in the same.

In Fig. 11, in case of a pull, the cotted 37 strikes the abutment *h*, or the cotted 42 the abutment *j*; in case of an impact, the cotted 75 37 strikes the abutment *i*.

In Fig. 12, in case of a pull, the disc 40 strikes the flange 87; in case of impact the flange 87 strikes the disc 40.

It is clear that the arrangement of the 80 additional auxiliary springs 48 (Figs. 13-17) can be used also in the constructions shown in Figs. 11 and 12, and that also in the constructions in Figs. 11 to 15, the cotters may be replaced by screw connections or 85 other rod couplings (Fig. 17) and that the power and the arrangement of the springs of one half of the car need not be the same in the other half of the car, but may be made different to suit the requirements. In case 90 of the auxiliary springs 48 (Figs. 14 to 17), more particularly when they are to be stiffer than the other springs, it is advisable that they be under less tension. For instance, in the construction shown in Fig. 17, 95 the coupling 80 may engage directly with the disc 33, while the sleeve 85 may be slightly shortened, so that in case of an impact the main spring 34 would be immediately affected and the spring 39 only later.

The dimensions in the central connection 100 43 should be preferably such that when, after complete expansion or contraction of the draw-gear, the rods 32 together with the connection part 43 have also become a rigid 105 unit; the play of the springs (with the exception possibly of that of the auxiliary springs 48 in Figs. 14 to 16, in the case of impact at opposite ends) should not have been completely utilized, so that the above-mentioned rigid unit could still be movable under the spring action. As in the case of violent impact at both ends, shocks and counter-shocks alternate at very short intervals of time, the springs will again become operative owing to the repeated movements of the draw and buffer gear produced thereby, and a very large portion of the force of impact 115 will be absorbed by the springs.

In the constructions described, the forces 120 act on the car frame not at one, but at several points, thus, for instance, in Fig. 11, in the case of a strong pull at one end on the abutment *i* by the spring 39, on the abutment *g* through the spring 34 and on the abutment 125 *j* by the cotted 42 limiting the movement, that is to say at three points, or in Fig. 17, in case of impact at one end, the forces act

on the abutment in the second half of the car by the main spring 39 in that half, and finally on the abutment *l* in the second half of the car by the auxiliary spring 48, and also in the first half of the car on the abutment *i* by the main spring 34 and on the abutment *j* by the main spring 39, that is to say, at four points.

We claim—

1. In a continuous draft mechanism for railway cars, a draft gear, springs thereon to permit longitudinal movement of the gear with respect to a car, a draw bar mechanism connected to said mechanism and comprising a frame slideable longitudinally of the car, a draw head member pivoted for lateral swing in said frame, and spring means on said frame to urge said member towards its alignment with said draft gear.
2. In a draft mechanism for railway cars of the type extending from end sill to end sill, a draft gear comprising two alined, spring held, connected, relatively movable sections, a slideable draw-bar mechanism connected at each end thereof, and a draw-head shank in each mechanism and having two pivotal points, one of said points being operative upon a pull and the other upon a push.
3. In a draft mechanism for railway cars of the type extending from end sill to end sill, a draft gear comprising two alined, spring held, connected, relatively movable sections, a slideable draw-bar mechanism connected at each end thereof, a draw-head shank in each mechanism and having two pivotal points, one of said points being operative upon a pull and the other upon a push, and spring means to normally hold said shank in pivotal operation with respect to one of said points.
4. In a draft mechanism for railway cars of the type extending from end sill to end sill, a draft gear comprising two alined, spring held, connected, relatively movable sections, a slideable draw-bar connection connected at each end thereof, a draw-head shank in each mechanism and having two pivotal points, one of said points being operative upon a pull and the other upon a push, and spring means to normally hold said shank in pivotal operation with respect to the point subjected to pull.
5. In a draft mechanism for railway cars of the type extending from end sill to end sill, a draft gear comprising two alined spring held, connected, relatively movable sections, a slideable draw-bar frame connected to one end of each section, said frame including a front cross member and at least one additional cross member, a draw-head shank passing through and movable in said front member, the end of said shank presenting a bearing against one of the members for compression thrust in the shank, and a sec-
- ond bearing longitudinally spaced therefrom taking the pull on said shank, said shank capable of longitudinal movement in the frame sufficient to bring one or the other bearing into operation, and spring means to hold said shank normally operative with respect to the latter bearing.
6. In a draft mechanism for railway cars of the type extending from end sill to end sill, a draft gear comprising two alined, spring held, connected relatively movable sections, a slideable draw-bar frame connected to an end of each section, said frame having a front cross member and at least one additional cross member, a draw-head shank passing through said front cross member, capable of swinging therein and of longitudinal movement in said cross member, the end of said shank rounded for seating in a corresponding recess of a member, when under compression, and means on said shank having a rounded surface arranged to engage a similar recess longitudinally spaced from the first recess, said means moved into operative engagement with its recess when a pull is exerted on said shank, and spring means to normally hold said means in operative engagement with its recess and simultaneously urge said shank to its middle position.
7. In a draft mechanism for railway cars of the type extending from end sill to end sill, a draft-gear comprising two alined, spring held, connected, relatively movable sections, a slideable draw-bar frame connected to an end of each section, said frame having a cross member, a draw-bar shank loosely passing through said member and capable of limited swing, said shank having a curved bearing surface engaging a corresponding seat in said member to communicate push to said frame, means on said shank having a curved face arranged to engage a corresponding recess in said frame when moved thereto to exert pull on the frame and said draw-gear sections to rigidly connect them to their respective frames.
8. In a continuous draft mechanism for railway cars, a draw head mechanism at each car end including a longitudinally sliding frame, a draft gear connected between said mechanisms and comprising two alined draw bar sections, means connecting the sections and permitting limited relative movement of each section with respect to said means, said means permitting both compression and tension forces to be transmitted from one section to the other, spring means independent of the car frame and interposed between said means and each section, and spring means arranged near the middle of the car to yieldingly hold each section.
9. In a continuous draft mechanism for railway cars, a longitudinally movable draw head mechanism at each car end, a draft gear

included between said mechanisms and comprising two alined draw bar sections, means connecting said sections and permitting limited relative longitudinal movement of each section with respect to each other and to said means, a spring between each section and said connecting means having limited bodily movement with respect to the car frame, and a plurality of springs for each section, said springs arranged for successive operation.

10. In a continuous draft mechanism for railway cars, a draw head mechanism at each car end and a draft gear included between said draw bar mechanisms, comprising two alined draw bar sections, connecting means between the sections permitting independent limited longitudinal movement of the sections, springs connecting each section to the car frame, an additional spring on each section, a pair of spring seats for each additional spring, one seat of each pair adjacent an end of said connecting means, whereby each of said latter springs may be operated independently of the car frame.

11. In a continuous draft mechanism for railway cars, a draw head mechanism at each car end, and a draft gear included between said draw head mechanisms, comprising two alined draw bar sections, means connecting said sections while permitting their limited longitudinal movement and permitting abutment of the ends of said sections at the limit of their movement in one direction, springs on each section for transmitting their forces to the car frame, additional springs at the inner end of each section independent of the car frame and having limited bodily movement with their respective sections, and a sleeve on the inner end of each draw bar mechanism that is slidale, said connecting means to compress the spring adjacent said means when the draw bar mechanism is under draft.

12. In a continuous draw bar mechanism, a draw bar having two alined sections, means connecting said sections while permitting relative longitudinal movement, main springs between the sections and car frame, and auxiliary springs on each section arranged to come into operation after a limited extent of movement of the section.

13. A continuous draft mechanism for railway cars, having two alined sections, means to slidably connect said sections, springs on the sections for connecting them to the floor frame of the car, and spring means independent of the floor frame on each section operating upon shock on said connecting means and therethrough on the alined sections.

14. In a draft mechanism for railway cars of the type extending from end sill to end sill, a longitudinally movable draw-bar mechanism adjacent each end sill, a draft

gear connected to said mechanisms between them and comprising two alined draw-bar sections, means connecting the sections together while permitting limited and independent longitudinal movement, a spring for each section adjacent said connecting means bodily movable with its section to a limited extent, and a spring near the end of each section compressible by the section but free of bodily movement.

15. In a draft mechanism for railway cars, of the type extending from end sill to end sill, a longitudinally movable draw-bar mechanism adjacent each end sill, a draft gear connected to said mechanisms between them and comprising two alined draw-bar sections, means connecting the adjacent ends of the sections together while permitting limited and independent movement, a spring for each section adjacent said means having limited bodily movement with its section, and a stationary spring for each section near the opposite ends thereof.

16. In a draft mechanism for railway cars, of the type extending from end sill to end sill, a longitudinally movable draw-bar mechanism adjacent each end sill, a draft gear connected to and between said mechanisms and comprising two alined sections, means connecting said sections together while permitting limited independent movement of the sections, the extent of movement of the sections being sufficient to permit of their abutting contact for the direct transmission of shock from one section to another, spring seats on each section and springs between said seats normally holding them in fixed spaced relation, said seats and springs bodily movable to a limited extent with its pertaining section, and each seat capable of separate movement upon compression of the spring between them.

17. In a draft mechanism for railway cars, of the type extending from end sill to end sill, a longitudinally movable draw-bar mechanism adjacent each end sill, a draft gear connected to said mechanisms between them and comprising two alined draw-bar sections, means connecting the adjacent ends of said sections while permitting limited independent movement and abutment of the sections, a spring carried by each section adjacent said connecting means, spring seats on the section between which said spring is included, said spring and seats having limited bodily movement with their section, and a sleeve on the end of each section slidale through said connecting means and acting on one of said spring seats, whereby said spring is compressed, after its bodily movement, upon a pull on the draft mechanism, and said seat is caused to abut said connecting means upon a push on said mechanism.

18. A draft mechanism for railway cars, comprising a draft gear yieldingly connected

to the car frame for longitudinal movement with respect thereto, a frame longitudinally movable with respect to said car frame and connected to said draft gear, a draw-head 5 having a shank pivoted for lateral swing in said frame, springs in said frame at both sides of said draw-head, rods in said frame on which said springs are mounted, said rods

slidable in the frame when the springs are

compressed, and a cross piece on the draw-head shank against which the ends of said rods abut to urge the draw-head into alignment with said draft gear. 10

In testimony that we claim the foregoing as our invention, we have signed our names.
